US00D593,974 S

(12) **United States Design Patent**
Yang et al.

(10) **Patent No.:** **US D593,974 S**
(45) **Date of Patent:** **** Jun. 9, 2009**

(54) **LCD TELEVISION SET**

(75) Inventors: **Jun-Ho Yang**, Kyunggi-do (KR);
Yun-Je Kang, Kyunggi-do (KR)

(73) Assignee: **Samsung Electronics Co., Ltd.**,
Kyunggi-do (KR)

(**) Term: **14 Years**

(21) Appl. No.: **29/269,013**

(22) Filed: **Nov. 17, 2006**

(51) **LOC (9) Cl.** **14-03**

(52) **U.S. Cl.** **D14/126**
